UNITED STATES PATENT OFFICE.

ADALBERT JOSEPHSON, OF NEW YORK, N. Y.

DESIGN FOR A DISPLAY-STAND.

49,434.

Specification for Design.

Patented July 25, 1916.

Application filed May 27, 1916. Serial No. 100,404. Term of patent 7 years.

To all whom it may concern:

Be it known that I, ADALBERT JOSEPHSON, a citizen of the United States, residing at New York city, in the county and State of New York, have invented a new, original, and ornamental Design for a Display-Stand, of which the following is a specification, reference being had to the accompanying drawing, forming part thereof.

In the drawing Figure 1 is an elevational

view of a display stand showing my new design; and Fig. 2 is an edge view thereof.

I claim:

The ornamental design for a display stand, as shown.

ADALBERT JOSEPHSON.

Witnesses:

CLARICE FRANCK,
JUDITH PARDEE.
